UNITED STATES PATENT OFFICE.

JOHN M. DOEHRER, OF BRIDGEPORT, CONNECTICUT.

LIQUID-DRAWING APPARATUS.

SPECIFICATION forming part of Letters Patent No. 770,271, dated September 20, 1904.

Application filed May 7, 1904. Serial No. 206,912. (No model.)

To all whom it may concern:

Be it known that I, JOHN M. DOEHRER, a citizen of the United States, and a resident of Bridgeport, in the county of Fairfield and

5 State of Connecticut, have invented certain new and useful Improvements in Liquid-Drawing Apparatus, of which the following is a specification.

My invention relates to an apparatus for 10 drawing beer or other like liquids; and it consists in certain details of construction to be more fully set forth in the following specification.

The object of my invention is to draw beer 15 or other like liquids from the top or bottom of the keg and automatically seal the outlet or bung when the draft-pipe is withdrawn to apply an air-pressure on the top of the beer to force it up through the draft-pipe 20 when drawing the beer.

To enable others to understand my invention, reference is had to the accompanying drawings, in which—

Figure 1 represents a sectional view of a 25 beer-keg and broken view of the pump connection. Fig. 2 is an enlarged detail view of the bung-plug and broken view of the draft-pipe to which said plug is removably attached. Fig. 3 is a central sectional view of Fig. 2.

30 Fig. 4 is an enlarged detail view of one of the rubber packing-rings with an inner metal shell therefor. Fig. 5 is an enlarged detail bottom plan view of the cap for the bung. Fig. 6 is an enlarged broken view, partly in section, of the bung and its cap, broken view of the lower end of the draft-pipe withdrawn from the bung, leaving the stopper or plug therein. Fig. 7 is an enlarged central sectional view of the bung, its cap, rubber pack- 35 40 45

ing-rings, air-valve, and broken view, partly in section, of the rubber air-pipe.

Its operation and construction are as follows:

1 represents a beer-keg; 2, a metallic bung 45 adapted as a permanent fixture of the keg. The end of the threaded portion of this bung may have the cutting edges or lips α , Fig. 1, to act as a tap in forming the threads in the head 1 α of the keg.

3 is the draft-pipe adapted to extend into 50 a room above.

4 is a hand-pump, and 5 the discharge-faucet.

The pipe 3, Fig. 1, extends through the central tapered hole 6, Fig. 7, to the bottom of 55 the keg. Referring to Fig. 6, the end of this pipe is either reduced to form the spring-fingers 7 by means of the kerfs 8 or a short piece of pipe having these spring-fingers may be firmly inserted in the lower end of the draft-pipe.

9, Figs. 2 and 3, is a hollow tapered plug closed at the bottom and having the holes 10 formed through the side, which holes serve both as outlets for the beer. The taper of 65 this plug corresponds to the tapered hole 6 of the bung, so that when the plug is drawn up into the bung in the manner presently to be described the keg is securely sealed.

11 and 12 are grooves rolled in the outer 70 surface of the plug 9, which will of course raise the annular projection 13 and 14 on the inside. When, therefore, the spring-fingers 7 are forced into the plug, the lower beaded ends 7 α of said fingers will spring outward 75 after passing by the lower annular projection 14 of the plug and temporarily secure said plug to said fingers.

When drawing, the beer will flow from the keg through the holes 10 of the plug up into 80 the pipe 3, and when the keg is emptied the draft-pipe is withdrawn. In pulling out this pipe the plug will be forced into the taper-hole 6 of the bung, where it will be firmly seated. This seating of the plug will offer 85 the necessary resistance to disengage the spring-fingers 7 from the plug, leaving the plug in the bung while the pipe is entirely removed, as shown at Fig. 6. The empty keg 90 is now hermetically sealed against the entrance of air or other deleterious matter.

15 is a spring-pin located in the bung 2, adapted to enter the lower groove 12 of the plug to prevent said plug accidentally falling out of the bung.

As before mentioned, my device is adapted 95 to draw liquid from the top or bottom of a keg. In drawing from the top the plug 9 is

pushed down until the spring-pin 15 enters the upper groove 11. This will bring the holes 10 in the plug below the end of the bung 2 to permit liquid to enter and pass up through 5 the draft-pipe. If desired, the plug can be reseated in the bung irrespective of the pipe 3 by means of a suitable key inserted in its open end and having means for engaging the lugs 16, Fig. 3, located near the bottom of 10 said plug.

17, Fig. 7, is a recess in the upper end of the bung 2 adapted to receive the threaded shank of the cap 18. This shank has the interrupted threads 18^a, Fig. 5, adapted to engage with the interrupted threads on the vertical walls of the recess 17 of the bung. The lower end of the air-tube connection is secured to this cap, as follows: 19 is a valve-casing having its lower threaded end 19^a 20 screwed into a threaded hole in the cap. 20 is a nipple screwed into the upper end of this casing, and to this nipple is secured the lower end of the rubber air-tube 21. The upper end of this tube is properly connected to the 25 pump above, Fig. 1. When, therefore, the pump-plunger descends, it will force air down through the tube 21 and channel 22 of the nipple and force the spring-actuated ball-valve 23 from its seat on the lower end of said 30 nipple. When this valve is opened, the air will enter the chamber 24 and from thence will pass down through the channel 25 of the cap 18 and casing 19 and into the keg through the tapered seat 6 of the bung, as follows: 26 is a recess in the cap 18, and 27 is a rubber packing-ring located at the bottom of this recess. This 35 ring is intended to firmly embrace the draft-pipe 3 to prevent the upward escape of the air by said pipe. The lower end of the recess 26 is enlarged to receive the lower and larger 40 rubber packing-ring 28. 29 is a metal ring (see also Figs. 4 and 5) within the rubber ring 28, and it has an internal diameter larger than the draft-pipe 3 to permit the passage of air 45 between said pipe and metal ring. This metal ring projects above the packing-ring 28 far enough to firmly engage the upper packing-ring, so that when the cap 18 is screwed down the lower packing-ring will be firmly seated 50 to prevent the escape of air between said ring and the bottom of the recess 17 of the bung 2, while the downward pressure of the cap 18 will force the metal ring 25 into the upper packing-ring 27 and crowd said upper ring 55 against the draft-pipe 3. The lower end of the air-channel 25 opens into the recess 26 of the cap 18 between the two rubber packing-rings 27 and 28. 29^a represents V-shaped 60 openings in that portion of the short metal ring 29 above the rubber ring 28 to admit the current of air inside of said ring and from thence to the seat 6 and the interior of the keg, as before mentioned. The arrows shown at Fig. 7 will show the course of the air-current

from the rubber pipe 21 to the lower end of 65 the metallic bung 2.

30, Figs. 6 and 7, is a ring of non-corrosive material let into the walls of the taper bore 6 of the bung 2 to prevent rusting in of the 70 plug 9 and also to resist wear.

When a short draft-pipe with the faucet close to the keg is used, the air tube or pipe can be dispensed with, as there will be sufficient head to the beer to force itself out. In such a case the casing 9 will be removed and 75 air-opening in the cap 18 will be plugged up by means of a screw or in any other effective manner; but when the beer is to be drawn to any great height air-pressure is necessary.

Applying air-pressure to the top of the beer 80 and drawing the beer from the bottom of the keg will give much better results, as more beer and less froth or foam will be discharged than when drawing from the top.

The automatic sealing of the keg, both when 85 filled and empty, directly from the draft-pipe is of great advantage, as the plug is always in its place and in readiness to be applied to seal the keg whether empty or full and the plug can never be lost or misplaced.

While I show holes in the side of the plug 90 whereby the beer or other like liquid is received into the pipe, it will be understood that these holes can be dispensed with in the plug and transferred to the pipe just above the plug 95 when said plug is temporarily secured to the entering end of the pipe, as shown at Fig. 2.

Having thus described my invention, what 100 I claim as new, and desire to secure by Letters Patent, is—

1. The combination, in a liquid-drawing apparatus, comprising a hollow bung adapted to be secured to a keg and having a tapered seat at its lower end, a removable hollow tapered plug adapted to fit said seat and having lateral holes to admit the liquid from the keg, said plug having annular grooves in its outer surface and correspondingly-annular projections on the interior, a discharge-pipe carrying spring-fingers at its lower end, the ends 110 of said fingers having raised beaded portions adapted to engage with the lower internal annular projection of the plug to reseat the same or prevent its dropping off from said pipe, a spring-actuated pin carried by the 115 bung and adapted to engage with either of the annular grooves of said plug, for the purpose set forth.

2. The combination, in a liquid-drawing apparatus, comprising a bung adapted to be secured to a keg and having a tapered seat in its lower end, a removable hollow tapered plug in the entering end of said bung, said plug having holes in its side to discharge liquid therefrom, a pipe adapted to pass through said bung into the keg and remove said plug on its 125 passage therethrough, means on the entering end of said pipe for temporarily securing

the plug thereto, said bung having a recess in its upper end, a cap removably secured thereto, an air-pipe connected with said cap, said cap having a recess in its under side, means 5 for forcing air into the recess of said cap and through an annular space between said pipe and bung, which annular space represents the seat for the plug, a valve to prevent the return of the air up the air-pipe, packing-rings in 10 the recess of the cap to prevent the escape of the air, for the purpose set forth.

3. The combination, in a liquid-drawing apparatus, comprising a bung adapted to be secured to a keg, a removable hollow plug in its 15 entering end, said plug having holes in its side to discharge the liquid therefrom, a pipe adapted to pass through said bung into the keg and remove said plug on its passage therethrough, means on the entering end of said 20 pipe for temporarily securing the plug thereto, said bung having a recess in its upper end, a cap removably secured to said recess, said cap having a recess in its lower end, a flexible

packing-ring at the bottom of said recess, and a flexible packing-ring at the mouth of said 25 recess, a metal ring embraced by said lower flexible packing-ring, the internal diameter of said metal ring being greater than the external diameter of said pipe, said metal packing-ring projecting against the under side of 30 the upper flexible packing-ring to effect an air-tight joint between said ring and pipe, said metal ring having air-passages, an air-pipe connected to said cap, means for forcing air into the recess of said cap so that, the air 35 will pass from thence through the air-passages of said metal ring, plug-seat of the bung and into the keg, for the purpose set forth.

Signed at Bridgeport, in the county of Fairfield and State of Connecticut, this 18th day of 40 April, A. D. 1904.

JOHN M. DOEHRER.
